MOISTENER FOR STAMPS OR THE LIKE

Wilbert C. Hopper, Washington, D. C.

Application December 3, 1957, Serial No. 48,763

Term of patent 14 years

(Cl. D74—10)

Fig. 1 is a side perspective view of a moistener for stamps or the like, showing my new design;

Fig. 2 is a front elevational view thereof drawn on larger scale;

Fig. 3 is a rear elevational view thereof;

Fig. 4 is a side elevational view, the side opposite thereto being similar in appearance; and

Fig. 5 is a top plan view thereof.

I claim:

The ornamental design for a moistener for stamps or the like, substantially as shown and described.
